UNITED STATES PATENT OFFICE

140,750

DESIGN FOR A UTILITY SHELF OR THE LIKE

Lee Hervey, Mountain Lakes, N. J.

Application December 20, 1944, Serial No. 117,007

Term of patent 14 years

(Cl. D33—3)

To all whom it may concern:

Be it known that I, Lee Hervey, a citizen of the United States and a resident of Mountain Lakes, in the county of Morris and State of New Jersey, have invented a new, original, and ornamental Design for a Utility Shelf or the like, of which the following is a specification, reference being had to the accompanying drawing, forming part thereof.

Fig. 1 is a front perspective view of a utility shelf showing my new design;

I claim:

The ornamental design for a utility shelf or the like, as shown.

LEE HERVEY.
